CARTRIDGE FEEDING MECHANISM FOR
AUTOMATIC GUNS

Samuel G. Green, Gray, Ga.

Application March 7, 1934, Serial No. 714,445

8 Claims. (Cl. 89—33)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to a cartridge feeding mechanism for automatic firearms.

The purpose of the invention is to provide a cartridge feeding mechanism which will accurately position a cartridge with its groove properly 10 presented to the extractor of the breech bolt, irrespective of variations in the length of the cartridge and irregularity of loading in the cartridge belt and without disturbing the alignment of the bullet and cartridge case or altering 15 the dimension between the bullet seat and the base of the cartridge case.

The invention consists in providing means for engaging a cartridge during the final stage of its movement through the feedway of a gun, displacing the cartridge axially to its proper position for extraction and then holding in such position against any force tending to move it forwardly in the feedway.

With the foregoing and other objects in view, 25 the invention resides in the novel arrangement and combination of parts and in the details of construction hereinafter described and claimed, it being understood that changes in the precise embodiment of the invention herein disclosed may 30 be made within the scope of what is claimed without departing from the spirit of the invention.

A practical embodiment of the invention is illustrated in the accompanying drawings, wherein:

Fig. 1 is a fragmentary longitudinal sectional view of a machine gun of the Browning type.

Fig. 2 is a plan view of the feedway of the gun showing a cartridge before it has been arrested in its passage through the feedway.

Fig. 3 is a similar view showing the cartridge 40 in position for extraction from its belt.

Fig. 4 is a view in side elevation looking into the feedway.

Fig. 5 is an enlarged plan view partly in section of the cartridge stop and guide member.

45 Fig. 6 is a section on the line 6—6 of Fig. 5.

Fig. 7 is a modified form of cartridge stop and guide member.

Fig. 8 is a plan view partly in section showing 50 a modified method of carrying the cartridge stop and guide member.

Fig. 9 is a view in elevation taken generally on the line 9—9 of Fig. 8.

55 Fig. 10 is a further modification of the guide member applicable to a gun of the Maxim type.

Fig. 11 is a view taken on the line 11—11 of Fig. 10.

Fig. 12 is still another modification of the guide member.

In the formation of cartridges the bullet is inserted in the mouth of the cartridge case. In the early method of assembly a uniform length of the cartridges was established by gaging between the nose of the bullet and the base of the cartridge case. Since the bullets and cases vary in length this method of assembly resulted in variable positions of the seating portion of the bullet so that when a cartridge was inserted in the barrel there was no assurance that the bullet was properly seated.

5 In order to remedy this situation the practice was adopted of assembling the round by seating the ogive of the bullet in an assembly die and accurately positioning the seating portion of the bullet with respect to the shoulder and the base 10 of the cartridge. Rounds assembled by this method do not have a uniform length as the sharpness of the point effects length.

15 In moving a cartridge into the feedway of a machine gun for the purpose of placing it in a position to be extracted from its belt by the breech bolt, it has been the practice to employ a rigid front guide plate which is engaged by the nose 20 of the bullet. The length of the cartridge therefore determines the position of the groove and rim of the cartridge case and since the length of the cartridge is variable the ultimate position of the groove and rim will also be variable.

25 The extractor on the breech bolt which is to engage the rim always has a fixed and definite position along the axis of the gun and relative to the feedway when the breech bolt is in battery. In consequence of the variable position of the groove and rim the extractor will fail to enter 30 the groove if the cartridge is short and of course the cartridge will not be extracted from its belt on rearward movement of the breech bolt.

35 The situation presented when the cartridge is too long is different. Since a cartridge that is too long has its base in the path of movement of the breech bolt and the extractor on the bolt, the cartridge case will be driven forwardly by these members and with the nose of the bullet engaging the front guide plate, the predetermined 40 position of the bullet seat will be changed. When the cartridge is provided with a supersensitive nose fuse this action will damage the fuse and 45 may result in a premature explosion. Furthermore, since the cartridge is not rigidly held in a position parallel to the breech bolt, the align- 50

ment of the bullet and cartridge case is destroyed. When a cartridge of this character is inserted into the barrel the bullet will not be properly engaged with its seat, and it will be unsymmetrically presented to the rifling. Gas leakage occurs and is followed by excessive erosion, and loss of accuracy and stability.

Another condition tending to disturb the alignment of the bullet and cartridge case is present when the round being moved into the feedway is not parallel to the axis of the gun. The loading mechanism of the gun possesses sufficient force to move the round into its final position parallel to the axis of the gun and in doing so it causes the bullet to be moved out of alignment with the cartridge case.

The improved device for overcoming all these defects and insuring correct presentation of the cartridge to the extractor and the breech bolt 0 and correct seating of the bullet in the barrel consists of a cartridge stop and guide member A positioned in the side of the feedway B of a machine gun opposite to the side of entry C. The gun illustrated is of the Browning type in which 5 an axially movable breech bolt D carries an extractor E and ejector F, both cooperating to withdraw a round of ammunition G from its belt H.

The cartridge guide member A (Figs. 2 and 3) is preferably formed from a single piece of metal 30 so that its bearing and contact surfaces may be accurately positioned by a single measurement from established surfaces wherever selected. The member A includes an arm 5 engaging the outer face of the receiver plate 6 of the gun and 35 secured thereto by rivets 7. The shoulder 8 at the forward end of the arm bears against the edge of the receiver plate at the rear of the feedway and provides one of the established surfaces from which measurements are made.

40 The under side of the member A is provided with a longitudinally extending groove 9 fitting on the edge of the receiver plate 6. The floor of the groove is in the plane of the main under surface 10 which rests on the trunnion block 11 of the gun. The surface 10 is used as a basis for vertical measurements.

The member A is formed with two curved cartridge engaging stop surfaces 12 and 13 which 50 arrest movement of the cartridge through the feedway of the gun and position it in alignment with the breech bolt which is to extract it from its belt. The front surface 12 is semi-circular and merges with the inner surfaces of spaced tangential fingers 14-14. As clearly shown in Fig. 4, 55 the front portion of the member A in which the surface 12 is formed has its under edge fitting in a groove 15 that extends transversely across the trunnion block 11. A slot 16 in the member A in rear of the surface 12 accommodates the finger 60 17 of the feed pawl 18 of the gun.

The stop surface 13 is an appreciable distance in rear of the stop surface 12 and is less than a semi-circle.

A pawl 19 having its front portion disposed in 65 a slot 20 in the member A is mounted on a pivot pin 21. The tail 22 of the pawl is adapted to engage the floor of the slot and limit rotational movement of the pawl under the influence of a spring 23 which acts on the rear end of the pawl. 70 A lip 24 on the rear end of the pawl 19 is adapted to engage in the groove of the cartridge.

As shown in Figs. 1, 2 and 3, a guide plate 25 defining the forward wall of the feedway is mounted in the raised front portion of the trunnion block 11 and yieldingly held by a spring 26.

A fixed pin 27 extending through a slot 28 in the plate 25 limits movement of the plate.

When the machine gun is in operation the breech bolt moves rearwardly on recoil and the extractor carried by the bolt withdraws a round from the feedway and holds the rim of the round in the T-slot in the front face of the bolt. During the continued rearward movement, the extractor is cammed downwardly to position the round in line with the bore of the barrel so that on forward movement of the bolt the cartridge is inserted into the chamber of the barrel. While this action is occurring, the feed pawl has engaged another cartridge and moved it across the feedway until arrested by the cartridge guide member A. As the bolt arrives in battery the extractor strikes the base of the positioned cartridge in the feedway and rides over it, and if the cartridge should still have its base in the path of movement of the bolt it will be struck by the bolt and moved forwardly. The stop surface 13 holds the cartridge against vertical displacement when the latter is struck by the extractor.

The cartridge stop and guide member A function in the following manner. As the cartridge enters the feedway, either by pulling on the belt or under the influence of the feed pawl 18, it approximately occupies its correct position longitudinally of the gun. If it is forward of its ultimate correct position due to improper loading in its belt, the nose of the bullet may engage the cam surface 29 on the front guide plate 25 and the cartridge and its belt will be moved rearwardly until the belt or the link of the belt engages the front face of the member A. The spring 26 of the front guide plate does not have sufficient force to displace the cartridge relative to its belt. If the base of the cartridge is still forward of its correct position the lip 24 of the pawl 19 will engage the rim of the cartridge and upon rotation of the pawl due to travel of the cartridge, the lip and consequently the cartridge will be moved rearwardly. When the cartridge has been arrested by the stop surfaces 12 and 13 its base will be in the correct position to fit in the T-slot of the bolt and its groove will be engaged by the extractor.

If a situation should arise where the base of the cartridge is so far to the rear that the lip of the pawl does not reach the groove, then the 50 cartridge is moved forwardly by the extractor on the breech bolt or by the breech bolt until the lip 24 snaps into the groove and securely holds the cartridge against further forward movement.

Irrespective of the variation in length of the cartridge or irregularity of loading in its belt, it is presented to the breech bolt and extractor without having the alignment of bullet and cartridge case disturbed and without altering the dimension between the seat of the bullet and the base of the round. The withdrawal of the cartridge from its belt in the feedway takes place in the usual manner, the link or belt being stripped by the front face of the member A. When inserted 60 in the chamber of the gun barrel the bullet is properly seated and the breech bolt is fully closed without head-space.

In the modification shown in Fig. 7, the pawl 30 is pivoted on a pin 31 at its front end so that its free end will move on a greater arc. A shoulder 32 on the pawl engages the rear face 33 of the cartridge stop and guide member 34 and limits movement of the pawl under the action of the spring 35.

In Figs. 8 and 9 the pawl 36 is carried by a block 37 which fits between the stop members 38 and 39. The pawl is partially disposed in a recess 40 in the center of the block and is mounted on a pin 41. The block is held in place by means of opposite studs 42-42 which enter apertures 43-43 in the stop members and also by means of studs 44 which enters apertures 45 in the stop member 39. The stop members 38 and 39 are present on existing guns and are selectively mounted on either side of the feedway depending upon whether the feed is to be from right to left or from left to right. The block being symmetrical may be reversed and mounted on either side of the feedway.

In guns of the Maxim type (Figs. 10 and 11) the extractor moves vertically upward as the breech bolt arrives in battery. In this situation the upper side of the cartridge is preferably engaged by a resilient guide member 46 which is fixed as to movement transversely of the gun by means of a bracket 47 secured to the top of the casing 48 as by rivets 49. The member 46 has two forwardly inclined arms 50-50 adapted to engage the groove of a cartridge being fed from left to right or from right to left and cam the cartridge to its position for extraction from the belt. The ends of the arms 50 are disposed in recesses 51 in the side plates 52 of the casing.

In Fig. 12 the front guide plate 53 serves to displace the cartridge and a plunger 54 serves to engage in the groove of the cartridge to hold it in proper position for extraction.

I claim:

1. In an automatic firearm, a receiver casing having a transverse cartridge feed channel, a yieldingly mounted plate in the front wall of the channel, a cartridge stop member disposed in the channel, a pair of spaced stop surfaces on said member, a pawl pivotally mounted in said member and having a lip on its rear end for engaging the groove of a cartridge case, a spring normally holding the pawl at an angle to the longitudinal axis of the firearm with its lip beyond the stop surfaces and in the path of movement of a cartridge moving across the feed channel.

2. In an automatic firearm, a receiver casing having a transverse cartridge feed channel, a cartridge stop member disposed in the channel, a pair of spaced stop surfaces on said member, a pawl pivotally mounted in said member and having a lip on its rear end for engaging the groove of a cartridge case, a spring normally holding the pawl at an angle to the longitudinal axis of the firearm with its lip beyond the stop surfaces and in the path of movement of a cartridge moving across the feed channel.

3. In an automatic firearm, a receiver casing having a transverse cartridge feed channel, a cartridge stop member disposed in the channel, stop surfaces on said member, a pawl pivotally mounted in said member and having a lip on its rear end for engaging the groove of a cartridge case, a spring normally holding the pawl at an angle to the longitudinal axis of the firearm with its lip beyond the stop surfaces and in the path of movement of a cartridge moving across the feed channel.

4. In an automatic firearm, a receiver casing having a transverse cartridge feed channel, a yieldingly mounted cartridge guide plate in the front end of the channel, means for limiting movement of a cartridge across the channel, a pawl mounted for movement in the plane of the feed channel, and a lip on the pawl for engaging a cartridge moving across the feed channel and seating in the groove of the cartridge.

5. In an automatic firearm, a receiver casing having a transverse cartridge feed channel, means for limiting movement of a cartridge across the channel, a pawl mounted for movement laterally of the feed channel and in the plane of the cartridge moving across the channel, and a lip on the pawl for engaging a cartridge moving across the feed channel and seating in the groove of the cartridge.

6. In an automatic firearm, a receiver casing having a transverse cartridge feed channel, a yieldingly mounted cartridge guide plate in the front of the channel, means for limiting movement of a cartridge across the channel, a lever normally at an angle to the longitudinal axis of the firearm, and means on the lever for engaging the rim of the cartridge and axially displacing the cartridge upon rotation of the lever to a position parallel to the axis of the firearm.

7. In an automatic firearm, a receiver casing having a transverse cartridge feed channel, means for limiting movement of a cartridge across the channel, a lever normally at an angle to the longitudinal axis of the firearm, and means on the lever for engaging the rim of the cartridge and axially displacing the cartridge upon rotation of the lever to a position parallel to the axis of the firearm.

8. In an automatic firearm, a receiver casing having a transverse cartridge feed channel, means for limiting movement of a cartridge across the channel, and a resiliently mounted rigid member disposed in the path of movement of a cartridge moving across the channel and arranged to engage the rim of the cartridge to hold the cartridge against forward displacement.

SAMUEL G. GREEN.
